UNITED STATES PATENT OFFICE.

ADAM DENNIS, OF FINDLAY, OHIO.

CUSPIDOR-LIFTER.

1,299,141.

Specification of Letters Patent.

Patented Apr. 1, 1919.

Application filed December 19, 1916. Serial No. 137,827.

To all whom it may concern:

Be it known that I, ADAM DENNIS, a citizen of the United States, residing at Findlay, in the county of Hancock and State of Ohio, have invented a new and useful Cuspidor-Lifter, of which the following is a specification.

This invention relates to a cuspidor lifter.

The object of the invention is to provide 10 a construction which will firmly and securely grip the cuspidor so as to allow the cleaning of the same without danger of the cuspidor falling out or becoming disengaged from the lifter.

15 The invention is especially applicable to cuspidors having an enlarged breast or base, a reduced neck and a flared top, rim or flange.

In the accompanying drawing, I have 20 illustrated one embodiment of my invention on a reduced scale and its application in which:—

Figure 1 is a front elevation of the same.

Fig. 2 is a side elevation.

25 Fig. 3 is a sectional view on the line 3—3 of Fig. 1, looking in the direction of the arrow.

Fig. 4 is a sectional view on the line 4—4 of Fig. 1, looking in the direction of the 30 arrow.

In the embodiment here illustrated, the lifter comprises a spring member 1, which consists of a single length of resilient wire bent intermediate its ends to form the handle 2, the sides of which converge downwardly to the points 3, as illustrated in Fig.

1. From the points 3, the side arms 4 diverge downwardly forming the resilient portions of the lifter. The lower portions of 40 the arms are looped in order to pass over the rim of the cuspidor and for this purpose, they are directed from the points 5 outwardly horizontally, as shown at 6 Fig. 1, bent downwardly at 7 around the rim of the 45 cuspidor and then directed inwardly horizontally as indicated at 8. The lowest portions of the arms are inclined and directed downwardly, as shown at 9 Fig. 1, to lie flat against the outside of the flared rim.

50 Attached to the ends 10 of the arms intermediate their lengths and at right angles thereto are arcuate jaws or grips 11 adapted to engage the reduced neck 12 of the cuspidor. The cuspidor is provided with the

usual breast 13 below the neck and the flared 55 rim 14 above the neck.

A slide 15 is loosely mounted upon the spring members or arms 4. When this slide is moved down to the portions 6 of the arms, the jaws will securely and tightly clamp the 60 cuspidor around its neck.

The construction above described provides a lifter by which the cuspidor may be picked up, carried about, held at an angle and tipped without danger of the same becoming 65 disengaged from the lifter. This advantage is secured by reason of the fact that the clamping jaws in my construction engage the cuspidor at the reduced portion or neck, while portions thereof both above and below 70 the neck are enlarged whereby slipping of the lifter either downwardly or upwardly is prevented. Furthermore, the inclined portions 9 assist in preventing movement of the lifter up and down relatively to the cuspidor and help to hold the same in position. 75

As will be seen from an inspection of Fig. 3, the handle or spring member of the lifter or portion thereof above the cuspidor extends at right angles and in a plane diametrically thereof leaving plenty of room to pour water into the cuspidor and to remove and wash out the contents therefrom.

While I have shown and described one embodiment of my invention, it is to be understood that I do not desire to be limited to the details of construction herein shown and described, for obvious modifications will be apparent to anyone skilled in the art.

What is claimed is:—

A cuspidor lifter comprising a spring member formed from a single length of resilient wire bent intermediate of its ends to form an elongated loop-like handle, the sides of which converge outwardly and 95 downwardly to form divergent side arms, diametrically opposite vertically disposed loops extending laterally from the lower ends of the arms and consisting of an outwardly extending substantially horizontal 100 portion, a downwardly curved portion and a lower inwardly extending portion, said loops being adapted to extend over the top and around and under the flared rim of the cuspidor, the wire below the loops being extended downwardly at an incline so as to bear flat against the rim above the neck, 105 horizontally disposed arcuate grips connect-

ed at an intermediate point to the ends of the wire, and arranged in a plane at right angles to the plane of the arms, each grip being of a length to partially encircle the 5 neck of a cuspidor, and means applied to said arms for releasing or gripping the lifter.

In testimony, that I claim the foregoing as my own, I have hereto affixed my signature in the presence of two witnesses.

ADAM DENNIS.
